UNITED STATES PATENT OFFICE.

JOHN T. PETERSON, OF MAYWOOD, ILLINOIS.

SOLDERING IRON.

Application filed September 27, 1920. Serial No. 412,998.

To all whom it may concern:

Be it known that I, JOHN T. PETERSON, a citizen of the United States, and a resident of Maywood, county of Cook, and State 5 of Illinois, have invented certain new and useful Improvements in Soldering Irons, of which the following is a specification.

My invention relates to improvements in soldering irons of the type comprising in 10 its complete organization suitable means for heating the bit, and it has for its principal object the provision of an improved construction and arrangement by reason of which an improved operation may be obtained.

Other objects will appear hereinafter.

My invention consists in the combinations and arrangements of parts hereinafter described and claimed.

20 The invention will be best understood by reference to the accompanying drawings forming a part of this specification, and in which,

Fig. 1 is a central section through my improved construction, the fuel tank being 25 partly broken away.

Fig. 2 is a fragmentary view, being substantially a section taken on line 2—2 on Fig. 1.

30 Fig. 3 is substantially a section taken on line 3—3 of Fig. 2.

Referring to the drawings, 5 indicates a tank of any approved type being shown in the form of a metal cylinder closed by 35 a cap 6 at one end and a cap 7 at the opposite end. The cap 7 is provided with an opening therethrough which in turn is closed by a plug 8, which is mounted in position by means of screw threads. As is clearly 40 shown in Fig. 2, the cap 7 is provided with an annular rib 9, being adapted to seat upon a gasket 10 of lead or other soft metal carried by the plug 8, upon the face of a laterally extending flange forming a part of the plug. By this construction a close fit is insured 45 between the plug and the cap. Wings 11 are mounted upon the plug for use in turning the plug into and out of position. An air pump is carried by the plug 8, the 50 pump in the construction shown comprising

a cylinder 12, and a piston rod 13, carrying at its outer end a head 14, by which the pump may be operated.

By means of the pump, which has a suitable outlet leading from cylinder 12 to the 55 interior of the tank 5, the air within the tank may be compressed. A pipe 15 is provided leading from tank 5 to a screw threaded socket 16 formed upon one side of a casting 17 in the form of a tube. The 60 opposite side of the casting 17 is provided with a thickened wall portion which is provided with a longitudinal opening 18, the front end of which communicates with the socket 16, by means of an annular cored out 65 opening 19. A laterally extending duct 20 extends from the rear end portion of the opening 18 and communicates with the interior of a sleeve 21, formed integrally with the casting 17. A tip 22, provided with a 70 tapered opening therethrough, is mounted by means of screw threads in the inner end of the sleeve 21. A stem 23 is adjustably mounted in the outer end portion of the sleeve 21, so as to be adjustable into and out 75 of contact with the tip 22, the adjustability in the construction shown being provided by means of screw threads. A handle 24 is mounted upon the turned outer end portion of the stem 23 for adjusting the position of 80 the stem, a locking nut 25 being provided for applying the desired resistance to the turning of the stem 23. In its inner end, the stem 23 is provided with a needle 26, which is of a shape and size to close the inner 85 end of the opening through the tip 22, the complete closure of the opening coming at the time when the stem 23 comes into contact with the end of the tip 22.

As is clearly shown in Fig. 1, the forward end of the tubular casting 17 is open so as to receive therein the tapered rear end of a soldering bit 27, which is held in position opposite the end of the tube by means of a yoke 28, the arms of which are mounted 90 in suitable sockets, formed in the wall of the tube, in the construction shown. The yoke 28 is formed of a steel bar which passes through an opening in the bit 27, having its end portions bent backward so as to cut 95 100

into the sides of the soft metal bit 27. Set screws 29 are provided for holding the arms of the yoke against withdrawal.

By the means just described, the copper bit 27 is held rigidly in position opposite the end of the tube, but out of contact therewith at all points.

In operation the tank 5 is provided with a quantity of fuel, such as gasoline, and the air in the tank above the level of the fuel is compressed by the use of the pumping means above described. When it is desired to heat the bit 27, the stem 23 is turned for opening the bore through the tip 22, whereupon a quantity of fuel is forced out through the tip into the tube 17. When the tube has been thoroughly heated by burning the gasoline therein, as is customary for generating the desired heat for tools of this type, the needle valve is regulated for controlling the flow of the vapor therethrough as will be readily understood. The flame which is projected forwardly from the end of the tube 17 is brought directly into contact with the bit 27 on all sides thereof at its rear end portion whereby it is very quickly brought to the desired temperature. When it is desired to discontinue the use of the device, the stem 23 is again turned for tightening the needle 26 in the bore of the tip 22, the contact of the stem with the rear end of the tip serving to prevent injury of the tip by the needle.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A device of the class described comprising a tube open at one end; means for delivering a stream of inflammable fluid to said tube to be burned at the open end thereof of sockets formed in the opposite wall portions of the tube at its open end thereof; a yoke having its arms secured in said sockets; and a soldering bit rigidly mounted on said yoke with its rear end tapered and extending into the tube but out of contact therewith.

2. In a soldering iron, the combination with a tube open at one end and means for delivering a stream of inflammable fluid to said tube to be burned at the open end thereof, of oppositely arranged sockets formed in the wall portion of said tube; a soft metallic bit adjacent the open end of said tube; a rod passing through said bit, the opposite ends of said rod being bent at right angles

at opposite sides of said bit, the ends of said rod being caused by the bending operation to cut into said bit for holding the bit rigidly in position thereon, said ends of said rod being fixedly secured in said sockets, substantially as described.

3. In a soldering iron, the combination with a tube bent at one end thereof, of a fuel tank for delivering a stream of fluid to said tube to be burned at one end thereof, a screw threaded valve, stem carried by said tube for regulating the flow of fluid thereto; a removable tip cooperating with said valve stem, there being a central passage, tapered at one end, through said tube; a needle removably carried by said stem adapted to close the opening through said tube by forward adjustment of said valve stem; a cap having a central opening therethrough mounted on one end of said tank; a plug screw-threaded in the opening of said cap; means for assuring a tight connection between said plug and said cap; and a pump carried by said plug and extending into said tank, substantially as described.

4. In a soldering iron, the combination with a tube open at one end and a soldering bit carried by and extending into said tube but out of contact therewith, of a fuel tank for delivering a stream of inflammable fluid to said tube to be burned at the open end thereof; a cap having an opening therethrough mounted on one end of said tank; a plug having an outwardly extending flange secured in the opening of said cap; a pump carried by said plug; an annular groove formed in said outwardly extending flange; a metallic gasket seated in said groove; and an annular rib formed on said cap adapted to engage said gasket, substantially as described.

5. A device of the class described comprising a tube; a bit carried thereby, and extending into said tube but not into contact therewith, the opposite ends of said bit being tapered; means for delivering a stream of inflammable fluid to said tube to be burned at one end thereof; a sleeve integrally formed on said tube; a valve stem screw-threaded in said sleeve; a removable tip having a tapered opening screw-threaded in one end of said sleeve; and a needle removably positioned in one end of said valve stem and projecting outwardly therefrom, said needle adapted to close the opening through said tip by a forward adjustment of said valve stem, substantially as described.

6. A soldering iron of the class described comprising a tube; ducts provided in the walls of said tube for delivering a stream of inflammable fluid to said tube; a soldering bit carried by and extending into said tube but out of contact therewith; and a rod member passing through an opening in said bit, having its ends bent substantially at

right angles adapted to fit in sockets provided in the opposite walls of said tube, said rod member removably mounted in said sockets; and means for holding said rod 5 against withdrawal substantially as described.

In testimony whereof I have signed my

name to this specification in the presence of two subscribing witnesses.

JOHN T. PETERSON.
